[57] CLAIM

The ornamental design for a combined headboard and storage unit, as shown and described.

DESCRIPTION

FIG. 1 is a perspective view of a combined headboard and storage unit, showing our new design;

FIG. 2 is a side elevational view, the opposite side being a mirror image thereof;

FIG. 3 is a front elevational view;

FIG. 4 is a top plan view;

FIG. 5 is a rear elevational view;

FIG. 6 is a bottom plan view;

FIG. 7 is an enlarged fragmentary view showing a seam on the top panel in greater detail;

FIG. 8 is an enlarged fragmentary view showing the bottom left corner in greater detail;

FIG. 9 is an enlarged fragmentary view showing the top right corner of the article in greater detail;

FIG. 10 is an enlarged fragmentary view showing the inside top right corner of the claimed article in greater detail.

FIG. 1
